United States Patent Office

Des. 204,667
Patented May 10, 1966

204,667

DELIVERY VAN

George C. Hoehne, Bellerose Village, N.Y., assignor to
The B. F. Goodrich Company, New York, N.Y., a
corporation of New York

Filed Aug. 3, 1965, Ser. No. 86,413

Term of patent 14 years

(Cl. D14—3)

Fig. 2

Fig. 1

Fig. 4

Fig. 3

FIG. 1 is a side view of the delivery van;
FIG. 2 is a plan view of the delivery van shown in FIG. 1;

FIG. 3 is a front view of the delivery van shown in FIG. 1; and

FIG. 4 is a rear view of the delivery van shown in FIG. 1.

The dominant features of my design reside in the portions shown in full lines.

I claim:

The ornamental design for a delivery van, substantially as shown and described.
